Primary Examiner — Marissa J Cash(74) *Attorney, Agent, or Firm* — Price Heneveld LLP(57) **CLAIM**

I claim the ornamental design for an aircraft, as shown and described.

DESCRIPTION

FIG. 1 is a top perspective view of an aircraft;
 FIG. 2 is a bottom perspective view of the aircraft;
 FIG. 3 is front elevation view of the aircraft;
 FIG. 4 is a rear side elevation view of the aircraft;
 FIG. 5 is a right side elevation view of the aircraft;
 FIG. 6 is a left side elevation view of the aircraft;
 FIG. 7 is a top plan view of the aircraft; and,
 FIG. 8 is a bottom plan view of the aircraft.
 The broken lines are environmental only and form no part of the claimed design.
